Attorney.

UNITED STATES PATENT OFFICE.

GEORGE T. TURNER, OF PHILADELPHIA, PENNSYLVANIA.

TOY PARACHUTE.

Application filed May 7, 1926. Serial No. 107,344.

The object of this invention is to provide a toy parachute of novel, inexpensive and efficient construction which may be comprised of as few as three parts; which may 5 be made largely or wholly of paper; which may be folded and assembled in quantities in compact form for distribution; and which may be used as an inexpensive advertising medium as well as a toy.

10 With the foregoing object in view, the invention consists of the elements and the combinations of them hereinafter described and claimed.

15 In the accompanying drawings, illustrating the invention,

Figure 1 is a side view of my improved parachute showing the position the parts thereof assume while the device is descending through the air.

20 Figure 2 is a top view of the spread sheet, showing the ends of the ribbon portions attached to the corners thereof and broken away.

Figure 3 is a side view of the device with 25 the spread sheet folded on the dot-and-dash lines shown in Fig. 2 into compact form in which the ribbon portions lie in close, substantially parallel relationship.

Figure 4 is a vertical section through the 30 bottom portion of the depending member and the weight, on line 4-4 of Fig. 3.

Figure 5 is a horizontal section through the same parts, on line 5-5 of Fig. 3.

Figure 6 is a view of the paper blank 35 from which the depending member is formed, the upper parts of the ribbon portions being broken away.

Figure 7 is a perspective of the weight member shown in Fig. 3.

40 Figure 8 is a perspective view of a modification of the weight member and the depending member attached thereto.

Figure 9 is a perspective view of the weight member shown in Fig. 8.

45 Figure 10 is a perspective view of another modification of the weight member and the depending member attached thereto.

Figure 11 is a side view of the parts shown in Fig. 9.

50 Figure 12 is a bottom view of the parts shown in Fig. 9.

Referring to the drawings, 2 designates a spread sheet, 3 a member attached to the

sheet 2 and depending therefrom, and 6 is a weight member carried by the bottom portion of the depending member 3.

The spread sheet 2 may be made square and formed of thin, light and flexible paper such as tissue or crepe paper of the kind used in paper napkins which may be folded 60 into the flat compact form shown in Fig. 3 and which may be readily opened from its compact form to its open or spread condition shown in Fig. 1.

The depending member 3 is formed of a 65 single piece of sheet material which may be a suitable grade of paper somewhat heavier or stiffer than the paper forming the spread sheet 2, and it comprises a bottom portion 7 and ribbon portions 8, four as herein illustrated, extending upwardly in side by side relationship from the top thereof. The upper end portions of the ribbon 8 extend over and are attached to the four corners of the spread sheet 2 by being pasted thereto, as 70 clearly shown in the drawings. The bottom portion 7 is bent on the line 9, Fig. 6, providing opposing side parts 10 between which the weight 6 is located.

The weight 6, as shown in Figs. 3 and 7 80 is in the form of a flat metal ring, and a common metal washer of suitable size may serve for this element. The weight 6 is retained in place between the side parts 10 by having the opposing surfaces of the parts 85 10 pasted together outwardly of and around the flat weight 6.

It will now be understood that when the 90 parachute is released at a suitable elevation or tossed into the air to float downwardly through the air, the weight 6 will cause the bottom portion 7 of the depending member 3 to descend first and the resistance of the air against the bottom surface of the spread sheet 2 will cause the same to open and retard the descent of the device and cause it to float downwardly at a slow rate of speed.

When the device is used as an advertising medium, the advertisements may be printed upon or otherwise suitably applied 100 to the spread sheet 2 and, if desired, to other parts of the device.

In the modification shown in Figs. 8 and 9, a small cylindrical weight 11 of wood or other suitable material is employed and it is 105 secured to the bottom portion 7 of the de-

pending member 3 by having the bottom portion 7 bent around the weight and pasted thereto.

In the modification shown in Figs. 10, 11 and 12, a small cubical weight 12 of wood or other suitable material is employed and two strips of paper 13 are bent around the bottom and four sides of the weight 12, crossing each other at the bottom of the weight and extending upwardly from the four sides thereof to provide four ribbon portions 14 which correspond with the four ribbon portions 8, shown in Figs. 1, 2 and 3. The strips 13 are secured to the weight 12 by being pasted to the bottom and the side walls thereof with which they are engaged.

I claim as my invention:

1. A parachute comprising a spread sheet, 20 a depending member formed of a single piece of sheet material and comprising a bottom portion and a plurality of ribbon portions extending upwardly therefrom and having their upper ends attached to the spread sheet, and a weight member carried by said bottom portion.

2. A parachute comprising a spread sheet, 30 a depending member formed of a single piece of sheet material and comprising a bottom portion and a plurality of ribbon portions extending upwardly therefrom and having their upper ends attached to the spread sheet, and a weight member carried by said bottom portion and retained within the embrace of opposing parts thereof.

3. A parachute comprising a spread sheet, 40 a depending member formed of a single piece of sheet material and comprising a bottom portion and a plurality of ribbon portions extending upwardly in side by side

relationship from the top thereof and having their upper ends attached to the spread sheet, and a weight member carried by said bottom portion.

4. A parachute comprising a spread sheet, 45 a depending member formed of a single piece of sheet material and comprising a bottom portion and a plurality of ribbon portions extending upwardly in side by side 50 relationship from the top thereof and having their upper ends attached to the spread sheet, and a weight member carried by said bottom portion and retained within the embrace of opposing parts thereof.

5. A parachute comprising a spread sheet, 55 a depending member formed of a single piece of sheet material and comprising a bottom portion and a plurality of ribbon portions extending upwardly therefrom and having their upper ends attached to the 60 spread sheet, said bottom portion being bent and providing opposing parts between which the weight is located, and said parts being pasted together outwardly of the weight to retain the weight between them. 65

6. A parachute comprising a spread sheet, 70 a depending member formed of a single piece of sheet material and comprising a bottom portion and a plurality of ribbon portions extending upwardly in side by side 75 relationship from the top thereof and having their upper ends attached to the spread sheet, a weight member carried by said bottom portion, said bottom portion being bent and providing opposing parts between which the weight is located, and said parts being pasted together outwardly of the weight to retain the weight between them.

In testimony whereof I affix my signature.

GEORGE T. TURNER.
